United States Patent Office

Des. 211,235

Patented June 4, 1968

211,235

INFANT'S TRAINING CHAIR

Clarence O. Hamilton and Edwin K. Moore, Columbus,
Ind., assignors to Hamilton Cosco, Inc., Columbus, Ind.,
a corporation of Indiana

Continuation of design application Ser. No. 3,734, Sept. 6,
1966. This application June 19, 1967, Ser. No. 7,508

Term of patent 14 years

(Cl. D4—5)

Fig. 1

Fig. 2

Fig. 3

Fig. 4

FIG. 1 is a perspective view of an infant's training chair embodying our new design;

FIG. 2 is a side elevation thereof;

FIG. 3 is a rear elevation thereof; and

FIG. 4 is a top plan view thereof.

The portions shown in dotted line are shown for illustrative purposes only.

This application is a continuation of our copending design application Ser. No. 3,734, filed September 6, 1966 and now abandoned.

We claim:

The ornamental design for an infant's training chair, as shown and described.
